UNITED STATES PATENT OFFICE.

GEORGE F. RAUCH, OF BIJOU HILLS, SOUTH DAKOTA.

DEVICE FOR FASTENING OVERSHOES OR RUBBERS TO SHOES.

1,268,616.

Specification of Letters Patent. Patented June 4, 1918.

Application filed February 12, 1917. Serial No. 148,161.

To all whom it may concern:

Be it known that I, GEORGE F. RAUCH, a citizen of the United States, residing at Bijou Hills, in the county of Brule and State of South Dakota, have invented a certain new and useful Improvement in Devices for Fastening Overshoes or Rubbers to Shoes, of which the following is a specification.

10 My invention relates to improvements in a device for fastening an overshoe or rubber to a shoe.

15 The object of my invention is to provide a cheap, convenient and efficient device for releasably attaching the rear end of an overshoe or rubber to a shoe, for the purpose of preventing the overshoe or rubber being pulled off in the mud from a shoe which it incloses.

20 A further object of my invention is to provide a simple device which may be a built up portion of the shoe or rubber.

25 Still another object of my invention is to provide novel fastening means, for attaching the rubber or overshoe to the shoe, which is easy to grasp for the purpose of attaching or detaching, and which may also be utilized for pulling the heel of the rubber or overshoe from the shoe, when the overshoe or rubber is to be removed from the shoe.

30 The novel features of my invention are hereinafter fully described and claimed.

35 In the accompanying drawing which illustrates the preferred embodiment of my invention,

Figure 1 is a perspective view of an ordinary rubber overshoe provided with my improvement.

40 Fig. 2 is a perspective view of a rubber overshoe mounted on an ordinary shoe and attached thereto with my improved fastening device.

Fig. 3 is an enlarged horizontal sectional view on the line 3-3 of Fig. 2.

45 Fig. 4 is a vertical sectional view on the line 4-4 of Fig. 3.

Fig. 5 is a perspective view of an eye having its points inwardly bent and which is adapted to be fastened to the rear side of a shoe and to receive the hook of the fastening device.

50 Similar reference characters designate similar parts in the different views.

1 designates the body of an ordinary rubber overshoe which is adapted to be fitted on an ordinary shoe 2, as shown in Fig. 2.

The rear end of the body 1 is provided with an upward extension comprising a strap 3, which is preferably a built-in part 60 of the body 1 and, preferably, extends upwardly from the upper edge of the rear end of the body 1.

The strap 3 may be of any suitable material, and it is preferably, of like material 65 and an integral part of the body 1. Such material may be of the ordinary kind, such as rubber or leather, used for articles of this character.

The strap 3 is provided with a hook 4, 70 which is, preferably, of inverted U-form, one of the arms thereof being embedded in the strap 3, and the other arm being at the inner side of said strap, so that it may be releasably attached to a securing device 75 fastened to the rear side of the shoe 2.

Such securing device may be of any desired type with which the hook 4 may have releasable engagement and support. In the drawing, I have shown a fastening device 80 comprising an eye consisting of a U-shaped clip 5, the arms of which are preferably pointed, so that they may be easily forced through the leather of the shoe 2. Each arm of the clip 5 is provided with two 85 shoulders 6 which are adapted to bear against the outer side of the shoe 2 when the eye or clip 5 is fastened thereto.

In fastening the eye or clip 5, the pointed ends thereof are forced through the leather 90 and then turned inwardly, as shown in Fig. 5, thereby clamping the eye or clip in a horizontal transverse position upon the rear side of the shoe 2.

When the overshoe 1 is slipped onto the shoe 2, the strap 3 is drawn upwardly so as to permit the hook 4 entering the eye or clip 5, from the upper side thereof. The overshoe will now be firmly held and cannot be pulled by the mud from the shoe.

100 It will be noted that the strap 3 is provided with an extension above the hook 4, which extension serves as a finger hold by which the strap may be easily grasped and pulled upwardly for the insertion of the 105 hook 4 in the eye or clip 5.

The strap 3 is preferably slightly elastic, so that, when engaged with the shoe 2, it

will be taut, thus eliminating the liability of the hook 4 becoming accidentally disengaged from the eye or clip 5.

I do not limit my invention to structure shown and described, as modifications, within the scope of the appended claim, may be made without departing from the spirit of my invention.

What I claim is:—

10 The combination with an over shoe or rubber having at its rear end a flexible strap extending upwardly above the upper

edge of the body of the over shoe or rubber, of an inverted U shaped hook located wholly at the inner side of the strap and having 15 one of its arms embedded in the strap, the latter having an extension above the hook which serves as a finger hold, and an eye adapted to be fastened to a shoe and to be releasably engaged by the other arm of the 20 hook.

In testimony whereof I have signed my name to this specification.

GEORGE F. RAUCH.
